UNITED STATES PATENT OFFICE

121,672

DESIGN FOR A WEDGE HEEL

Anthony Cocozella, Lynn, Mass., assignor to
United Shoe Machinery Corporation, Borough
of Flemington, N. J., a corporation of New Jersey

Application May 8, 1940, Serial No. 92,227

Term of patent 14 years

To all whom it may concern:

Be it known that I, Anthony Cocozella, a citizen of the United States, residing at Lynn, in the county of Essex and Commonwealth of Massachusetts, have invented a new, original, and ornamental Design for Wedge Heels, of which the following is a specification, reference being had to the accompanying drawing, forming part thereof.

In the drawing,

Fig. 1 is a perspective view of a wedge heel showing my new design, the heel being posi-

tioned so as to show the upper or attaching face thereof;

Fig. 2 is a perspective view of the heel positioned so as to show the lower surfaces thereof;

Fig. 3 is a rear elevational view of the heel; and

Fig. 4 is a bottom plan view of the heel.

I claim:

The ornamental design for a wedge heel, substantially as shown.

ANTHONY COCOZELLA.
